US00D854060S

(12) **United States Design Patent** (10) **Patent No.:** **US D854,060 S**
(45) **Date of Patent:** **** Jul. 16, 2019**

(54) **VOLUME TANK**

(71) Applicant: **WORTHINGTON INDUSTRIES, INC.**, Columbus, OH (US)

(72) Inventors: **James M. Getter**, Sunbury, OH (US); **Kassandra M. Williams**, Dublin, OH (US); **Xiaoting Liang**, Plain City, OH (US)

(73) Assignee: **WORTHINGTON INDUSTRIES, INC.**, Columbus, OH (US)

(**) Term: **15 Years**

(21) Appl. No.: **29/621,594**

(22) Filed: **Oct. 10, 2017**

(51) LOC (11) Cl. **15-09**

(52) U.S. Cl.

USPC **D15/138**; D23/206

(58) **Field of Classification Search**

USPC D15/150, 151, 152; D23/206; D29/101.2

CPC B60P 1/16; B60P 1/36; B60P 1/42; B60P 1/286; B60P 3/30

See application file for complete search history.

(57) **CLAIM**

The ornamental design for a volume tank, as shown and described.

DESCRIPTION

FIG. 1 is a perspective view of a volume tank showing a new design;

FIG. 2 is a left side view of the volume tank illustrated in FIG. 1;

FIG. 3 is a right side view of the volume tank illustrated in FIG. 1;

FIG. 4 is a bottom view of the volume tank illustrated in FIG. 1;

FIG. 5 is a top view of the volume tank illustrated in FIG. 1;

FIG. 6 is a front view of the volume tank illustrated in FIG. 1; and,

FIG. 7 is a rear view of the volume tank illustrated in FIG. 1.

1 Claim, 7 Drawing Sheets
